VAPORIZER

Ormsby McHarg, New York, N. Y.

Application March 23, 1938, Serial No. 197,548

2 Claims. (Cl. 128—192)

This invention relates to vaporizers and more particularly to those used in generating heated vapors for inhalation, and an object of the invention is to provide a device of this type having improved features of construction contributing to increased safety in operation and satisfaction in use.

This and other objects which will be apparent to those skilled in the art are accomplished by the present invention one embodiment of which is illustrated in the accompanying drawing in which,

Fig. 1 is a view in elevation of a complete vaporizer outfit constructed in accordance with one embodiment of this invention;

Fig. 2 is a transverse sectional view through the vaporizer shown in Fig. 1;

Fig. 3 is a sectional view on the line 3—3 of Fig. 2.

The particular embodiment of the invention which has been chosen for illustration comprises a body member 5 having a recess 6 for receiving a cup 7 of heat transferring material, preferably aluminum, the flaring end 8 of which is secured to a shoulder 9 formed in the recess 6. The joint between the container and the shoulder 9 is sealed so that no liquid or vapor can enter the space between the wall of the cup 7 and the wall of the recess 6. The recess extends upwardly above the cup within a wall 10.

A nozzle member 11 in the form of a cap threaded or otherwise secured to the body member encloses the recess and the diameter of the wall 12 of the cap is such as to provide a space 13 between the cap and the recess wall 10. The nozzle has the usual nozzle-shaped opening 14 through which vapor is inhaled by the user. A tubular extension 15 is formed within the nozzle member and extends to a point slightly below the top of the wall 10 of the body member thus forming an annular recess 16, preferably of greater capacity than the cup 7, into which fluid from the cup 7 will flow if the vaporizer is tipped beyond the horizontal and the danger of boiling fluid running out of the nozzle 14 avoided.

The wall 12 of the nozzle member has one or more air openings 17 positioned at a level below the top edge of the wall 10 so that air drawn therethrough is compelled to follow a circuitous path over the top of the wall 10 downwardly into the recess where it picks up the heated vapor and then passes outwardly through the nozzle 14.

An electrical heating element 18 is located in the recess 6 between the wall of the cup 7 and

the wall of the recess. The heater leads extend through the bottom of the body member 5 to terminals 19 which are housed within a base cap 20 threaded to the body member.

The complete device includes the usual plug 21 and switch 22.

In use, the nozzle cap is removed and the fluid-heating cup 7 filled with whatever liquid it is desired to use. The cup is preferably formed so as to hold approximately 2 c. c. of liquid. The cap is then replaced and current supplied to the heater element which results in quickly vaporizing the fluid in the container. Upon inhaling, air is drawn through the air opening 17 as above described. If the device is tilted beyond the horizontal, the user is protected against the highly heated liquid flowing out of the nozzle opening 14 by the liquid receiving pocket 16 which is formed between the wall of the cap and the inwardly-extending tubular projection 15. The liquid will flow into this pocket and the user is thus protected against dangerous burns. Except for the vaporizing cup 7, the material employed is a non-conductor of heat so that the device can be safely and satisfactorily used.

It will be apparent that the invention can be variously modified and adapted within the scope of the appended claims.

I claim:

1. A vaporizer comprising a recessed body member, a cup, means for securing said cup in said recess so as to form a closed space between the wall of said recess and said cup, a heating element in said space, a nozzle member having an outer wall surrounding and spaced from the wall of said recess with air inlet openings communicating with said space, and an inner tubular extension located opposite said recess and forming a pocket for accommodating fluid spilt from said cup.

2. A vaporizer comprising a recessed body member, a flanged cup located in said recess with the flange engaging the wall thereof to form a closed space between said wall and said cup, a heating element in said space, a nozzle member having an outer wall surrounding and spaced from the wall of said recess with air inlet openings in said outer wall communicating with said space, and an inner tubular extension surrounding the nozzle outlet, located opposite and extending into said recess and forming a pocket for accommodating fluid spilt from said cup.
